TIRE

Edward H. Wallace and Russell W. Vance, Grosse Pointe,
and James M. Lane, St. Clair Shores, Mich., assignors
to United States Rubber Company, New York, N.Y., a
corporation of New Jersey

Application September 15, 1958, Serial No. 52,636

Term of patent 14 years

(Cl. D90—20)

Fig. 1

*Fig. 2**Fig. 3**Fig. 4*

Fig. 1 is a perspective view of a tire embodying our new design, it being understood that the full line portion is repeated throughout the circumference of the tire shown by means of broken lines.

Fig. 2 is an enlarged fragmentary plan view of the full line portion of Fig. 1.

Fig. 3 is a fragmentary sectional view taken substantially on the plane indicated by line III-III of Fig. 2, and

Fig. 4 is an enlarged fragmentary perspective view of the right-hand edge portion of the tread.

The characteristic features of the design of the tire disclosed reside in a tread provided with ribs, the center ribs having a substantially honeycomb pattern of slots and a multiplicity of essentially cylindrical traction elements individually surrounded by said slots, substantially as shown.

We claim:

The ornamental design for a tire, substantially as shown and described.
